ELECTRODE HOLDER

Lloyd W. Weeks, Inglewood, Calif., assignor of
one-fourth to Charles F. Briscoe and one-
fourth to Fred Nelson, Los Angeles, Calif.

Application May 24, 1938, Serial No. 209,681

6 Claims. (Cl. 219—8)

This invention relates generally to electrode holders for use in electric welding, and is particularly concerned with improvements in holders of the jaw type, i. e. in which the welding electrode or rod is retained between jaws extending longitudinally beyond the handle of the tool.

The present holder may be described generally as comprising a hollow handle made of suitable insulating material, and a pair of jaws extending forwardly of the handle and adapted to be spread by relative movement laterally of the handle axis. One of my primary objects is to provide within the handle and concealed from exposure to flying metal, suitable means, preferably in the form of a coil spring, for exerting a jaw closing force. Another important object is to provide a type of connection between the jaws to adapt them to the endwise application of closing force by the handle contained spring. Other features of the invention have to do more particularly with features of construction whereby the holder may be cheaply manufactured with a minimum number of parts which may be readily and easily assembled.

In the preferred forms of the invention, one of the jaws is formed integrally with a shank extending longitudinally within the handle. The other (movable) jaw is connected with a jaw spreading lever and with the shank in a manner causing the jaw to move longitudinally toward the handle as the jaw opens, and to compress the spring contained in the handle. In this manner I obtain an efficient leverage in applying the spring force to the jaw, and in so doing keep the parts in very compact and simple arrangement. An annular member movable longitudinally in the shank transmits the spring force to the jaw and serves also to provide a closure for the inner end of the handle to guard the spring against contact by hot metal particles.

The above mentioned objects, as well as additional features and details, will be more fully understood from the following description of certain typical and illustrative forms of the invention as shown in the accompanying drawing. In the drawing:

Fig. 1 is a view showing one form of holder embodying the invention, the tubular handle appearing in longitudinal section and the jaws in closed position;

Fig. 2 is a view similar to Fig. 1 showing the jaws spread;

Fig. 3 is a view similar to Fig. 1 illustrating a variational form of the invention;

Fig. 4 is a fragmentary section on line 4—4 of Fig. 1; and

Fig. 5 is a section on broken line 5—5 of Fig. 3.

Referring first to the form of the invention shown in Figs. 1 and 2, the handle comprises a hollow tube 10 made of suitable insulating material such as Bakelite or the like. Extending forwardly of the handle is a pair of jaws 11 and 12, the latter of which is longitudinally recessed at 13 and is provided with a series of teeth or serrations 14 at opposite sides of the recess. In closed position, the jaw 11, being narrower than jaw 12, closes into engagement with the outer end of recess 13. By spreading the jaws, the welding rod or electrode may be inserted transversely between them so as to be held by jaw 11 against the serrated edges 14 of the other jaw.

Jaw 12 is integral with a shank 15 extending centrally within the handle 10 and threaded at 16 into a block 17 having a socket 18 which receives the end of the cable 19 through which current is supplied to the electrode. The body of block 17 is spaced at 20 from the handle, and is provided with end flanges 21 of polygonal cross section, the flattened corners 22 of the flanges being received within longitudinally extending shallow grooves 23 in the inner surface of the handle, to prevent rotation of the latter. As will be understood, electric current flows from cable 19 through the block 17, shank 15 and jaw 12 to the welding electrode held between the jaws.

The jaws are operated by a lever 24 having an insulation covered handle 25 and a yoke 26 straddling the jaw 11 and pivotally connected to jaw 12 by a pin 27 extending transversely through the shank end of the jaw, see Fig. 4. The yoke 26 also is pivotally attached to jaw 11 at a point forwardly of the pin 27 by means of pin 28. The inner end of jaw 11 is slotted at 29 to provide clearance between the jaw and the curved portion of shank 15 at the inner end of jaw 12. By pivotally connecting the yoke to both jaws and offsetting pin 28 forwardly with respect to pin 27, the jaws are caused to move relatively longitudinally upon spreading, i. e. as jaw 11 is swung open, it is at the same time shifted longitudinally toward the handle 10.

The capacity for longitudinal movement thus given jaw 11 permits the application of closing force to the jaw by a spring contained within the handle 10. The inner tapered end 11a of the jaw bears against a sleeve or ring 30 which is pressed against the jaw by coil spring 31 encir-

clinging the shank 15. The outer surface of ring 30 is shaped as illustrated to provide shoulders 32 at the point of engagement with the jaw, and the ring is movable longitudinally of the shaft 5 to permit movement of the jaw between open and closed positions. The spring compression is adjustable by nut 33 threaded on the shank and engaged by a metal washer 34. Fiber washers 35 and 36 insulate the spring from the current flow through the shank.

By pressing lever 24 toward the handle 10, jaw 11 is opened to the position of Fig. 2, moving ring 30 along the shank and compressing spring 31. After the electrode is inserted between the 5 jaws, the spring continues to exert a closing force against jaw 11 to securely hold the electrode. By reason of the leverage efficiency in the yoke connection between the jaws, it is possible to use a strong spring which will cause the jaw to tightly 10 and securely hold the electrode. It may be mentioned that the ring 30 has a further function in that it provides a closure for the handle bore, preventing hot metal particles from entering the handle and contacting the spring. By 15 thus keeping the spring fully protected and housed within the handle, the spring tension may be maintained indefinitely, a feature of particular importance in view of the conditions under which holders of this type are used.

30 The holder shown in Fig. 3 is similar in all respects to the previously described form of the invention, except as to the connection between the operating lever and the jaws. In the variational form, the lever 38 extends through slot 39 formed centrally within jaw 11 from its inner end, see Fig. 5, and into slot 40 within the shank end of jaw 12, pivotally connected to the jaws by pins 41 and 42. Lever 38 imparts to the jaws the same type of movement as in the first described form, pin 41 being set forward with relation to pin 42, so that jaw 11 opens by movement against the ring 30 to compress the spring.

I claim:

45 1. In an electrode holder of the character described, the combination comprising a hollow handle, a pair of jaws extending forwardly of the handle and adapted to be spread apart laterally of the handle axis, means for passing electric current through the handle to one of said jaws, means within the handle for closing one of the 50 jaws against the other, and a lever pivotally attached to one of the jaws and extending transversely across the other jaw, said lever being movable in the plane of the handle to spread the jaws.

55 2. In an electrode holder of the character described, the combination comprising a hollow handle, a pair of jaws extending forwardly of the handle and adapted to be spread apart laterally and at the same time to be moved relatively longitudinally of the handle axis, means

for passing electric current through the handle to one of said jaws, a spring within the handle for closing one of the jaws against the other, and means for spreading and moving the jaws relatively longitudinally against the resistance of said spring.

3. In an electrode holder of the character described, the combination comprising a hollow handle, a pair of jaws extending forwardly of the handle and adapted to be spread apart laterally of the handle axis, a conductor shank extending from one of the jaws longitudinally within the handle, a coil spring encircling said shank within the handle for closing one of the jaws against the other, and means for opening and moving the jaws relatively longitudinally so that one of the jaws compresses said spring.

4. In an electrode holder of the character described, the combination comprising a hollow handle, a pair of jaws extending forwardly of the handle and adapted to be spread apart laterally of the handle axis, a conductor shank integral with one of said jaws and extending longitudinally within the handle, jaw spreading means pivotally connected to said shank and to the other jaw so that in opening, the last mentioned jaw moves longitudinally of the shank toward the handle, and a coil spring surrounding said shank within the handle and resisting such movement of the jaw.

30 5. In an electrode holder of the character described, the combination comprising a hollow handle, a pair of jaws extending forwardly of the handle and adapted to be spread apart laterally of the handle axis, a conductor shank integral with one of said jaws and extending longitudinally within the handle, jaw spreading means pivotally connected to said shank and to the other jaw so that in opening, the last mentioned jaw moves longitudinally of the shank toward the handle, a ring movable longitudinally on said shank and engaging the inner end of the movable jaw, and a coil spring surrounding the shank within the handle and pressing said ring into engagement with the jaw to resist its opening movement.

35 6. In an electrode holder of the character described, the combination comprising a hollow handle, a pair of jaws extending forwardly of the handle and adapted to be spread apart laterally of the handle axis, a conductor shank integral with one of said jaws and extending longitudinally within the handle, a jaw spreading lever extending opposite said handle and having a yoke portion pivotally connected to said shank and to the other jaw so that in opening, the last mentioned jaw moves longitudinally of the shank toward the handle, and a coil spring surrounding said shank within the handle and resisting such movement of the jaw.
